CORNER FOR CORNER BEADS

Filed June 29, 1925

Inventor:
Charles H. Richards,
By Sympathetic, Christian, Miles,
H. A. T. G.

UNITED STATES PATENT OFFICE.

CHARLES H. RICHARDS, OF AURORA, ILLINOIS, ASSIGNOR OF ONE-HALF TO RICHESTO MANUFACTURING COMPANY, A CORPORATION OF ILLINOIS.

CORNER FOR CORNER BEADS.

Application filed June 29, 1925. Serial No. 40,381.

This invention relates to improvements in corner for corner-beads, and more especially to such a corner adapted for use in connection with metallic corner-beads.

By the use of my invention it is possible to form the corner between adjacent strips of corner-bead accurately and quickly without requiring laborious fitting, adjusting or cutting of metal. By the use of my invention also, for example, the right angle corners formed by the corner-beads around a window casing may be quickly and accurately made.

My improved device is cheap to make and is neat and durable.

Other features and advantages of my invention will appear more fully as I proceed with my specification.

In that form of device embodying the features of my invention, shown in the accompanying drawings, Figure 1 is a view in front elevation of my improved corner for corner-beads, Fig. 2 is a view taken as indicated by the line 2 of Fig. 1, Fig. 3 is a view in side elevation of the corner piece itself, and Fig. 4 is a bottom view of the same.

As shown in the drawings, the corner-bead is made of a single strip of sheet metal curved longitudinally along its length at the center to form a bead proper 10 which thus presents a rounded transverse outer surface having elongated straight edges 11, 11 to provide the ground or gage to which the plasterer may finish his work and further to provide means for straightening the plastered structure at the corners.

At the edges 11, the metal is bent back as indicated at 12 to partially overlap and lie parallel with the side margins of the bead portion 10. The portions 12 are preferably spaced from the side margins of the portion 10 a distance equal substantially to the thickness of the metal. The metal from the inner edges of the portions 12 is bent away from the bead portion 10, the two sides being substantially parallel for a short distance, to form the narrowed throat 13. From the inner end of the throat, the metal is bent outwardly to form the two side wings 14, 14, which lie substantially at right angles to each other and serve to attach the bead to the structure to be plastered. These wings are provided with the holes 15, 15 adapted to receive the nails 16 which may nail the

corner-bead to the structure to be plastered. The wings are also provided with the usual perforations 17 having the flanges 18 which serve as keys for the plaster.

The corner piece itself is shown in Figs. 60 3 and 4. This is preferably made out of pressed steel and it will be seen that this corner piece in cross-section is substantially the same as the bead portion proper 10 of the corner-bead. The corner piece itself is 65 indicated in general by 19. This piece comprises the corner portion proper indicated by 20 which forms a right angle for the corner-bead proper as shown. The portion 20 is provided at each end with an ear or 70 lug 21 which is also curved transversely to conform to the curvature of the bead 10. The lug or ear 21 of the corner piece is adapted to fit into the space between the bead portion 10 and the bent-back portions 75 12. The corner piece 19 is provided with a shoulder or offset 22 where the ear 21 joins the corner portion 20. This offset or shoulder 22 is substantially the thickness of the metal and is adapted to butt against the end 80 of the bead portion 10 of the corner-bead and form a continuation thereof. (See Fig. 1.)

The corner piece 19 is preferably stiff and rigid so that when the ears or lugs 21, 85 21 are in place in the ends of the corner-beads, a stiff and rigid corner connection for the two corner-beads will be made. The ear 21 is adapted to fit snugly in the end of the corner-bead piece. It will be seen that 90 by the use of my invention, a corner for corner-beads may be accurately and quickly formed without requiring any laborious cutting or fitting. If it attempted to make a corner between the two beads without the 95 use of such a corner piece it is necessary to do very accurate diagonal cutting and fitting of the two ends of the corner-beads in order to make the mitered corner. By the use of my invention, all such work is 100 done away with.

While I have shown and described certain embodiments of my invention, it is to be understood that it is capable of many modifications. Changes, therefore, in the construction and arrangement may be made without departing from the spirit and scope 105 of the invention as disclosed in the appended claims, in which it is my intention to claim all novelty inherent in my inven- 110

tion as broadly as possible in view of the prior art.

What I claim as new, and desire to secure by Letters Patent, is:

5. 1. A corner-bead structure comprising; a corner-bead formed from a strip of metal bent longitudinally to provide a bead portion proper, portions of said metal being bent backwardly upon itself at the edges 10 of said bead portion proper, thence inwardly substantially parallel to form a narrowed throat and thence away from each other substantially at right angles to form wings for attachment to a structure to be plastered; and a corner piece having a corner portion forming a right angle and adapted 15 to form a continuation of and right angled connection between the two bead portions proper of two corner-beads lying at right angles to each other, said corner piece being provided at each end with an ear adapted to be inserted into the end of one 20 of the corner-beads in the space between the bead portion proper and the portions of the 25 metal bent backwardly upon itself at the edges of said bead portion.

2. A corner-bead structure comprising; a corner-bead formed from a strip of metal bent longitudinally to provide a bead portion proper, portions of said metal being bent backwardly upon itself at the edges of said bead portion proper, thence inwardly substantially parallel to form a narrowed throat and thence away from each other substantially at right angles to form wings for attachment to a structure to be plastered; and a corner piece having a corner portion forming a right angle and adapted 35 to form a continuation of and right angled connection between the two bead portions proper of two corner-beads lying at right angles to each other, said corner piece being provided at each end with an ear adapted to be inserted into the end of one 40 of the corner-beads in the space between the bead portion proper and the portions of the metal bent backwardly upon itself at the edges of said bead portion.

ing provided at each end with an ear adapted to be inserted into the end of one of the corner-beads in the space between the bead portion proper and the portions of the metal bent backwardly upon itself at the edges of said bead portion proper, thence inwardly substantially parallel to form a narrowed throat and thence away from each other 50 substantially at right angles to form wings for attachment to a structure to be plastered; and a corner piece having a corner portion forming a right angle and adapted to be held snugly in said corner-bead between the corner-bead portion proper and the backwardly bent portions of metal at its edges.

3. A corner-bead structure comprising; a corner-bead formed from a strip of metal bent longitudinally to provide a bead portion proper, portions of said metal being bent backwardly upon itself at the edges of said bead portion proper, thence inwardly substantially parallel to form a narrowed throat and thence away from each other 55 substantially at right angles to form wings for attachment to a structure to be plastered; and a corner piece having a corner portion forming a right angle and adapted to form a continuation of and right angled 60 connection between the two bead portions proper of two corner-beads lying at right angles to each other, said corner piece being provided at each end with an ear adapted to be inserted into the end of one 65 of the corner-beads in the space between the bead portion proper and the portions of the metal bent backwardly upon itself at the edges of said bead portion, said corner piece being provided with a shoulder 70 or offset at the juncture between the ear and the corner portion, whereby the outer surface of said corner portion will lie flush with the outer surface of the bead portion proper of the corner-bead.

In testimony whereof I have hereunto set my hand this 26th day of June, 1925.

CHARLES H. RICHARDS.
